PROCESS FOR REDUCING THE OLEFIN CONTENT OF AN OLEFINIC DISTILLATE

Vladimir Haensel and Vladimir N. Ipatieff, Chicago, Ill., assignors to Universal Oil Products Company, Chicago, Ill., a corporation of Delaware

Application October 12, 1942, Serial No. 461,772

4 Claims. (Cl. 196—44)

1

This invention relates to a method for the reduction of the olefin content of a hydrocarbon fraction. More specifically it is concerned with a method of reducing the bromine number of a gasoline boiling range fraction to prepare a hydrocarbon fraction suitable for aviation fuel purposes.

Cracking or reforming operations generally produce gasolines which have a high initial octane number but which have a relatively low lead susceptibility because of their high olefin content. For this reason, gasolines produced by these processes are usually unsatisfactory as aviation fuel base stocks.

We have found that a gasoline of low olefin content may be obtained by contacting an olefinic gasoline substantially free of added higher boiling hydrocarbons with a particular type of silica base catalyst at proper operating conditions. We have found that when the proper operating conditions are employed, that fraction of the product which boils within the boiling range of the charging material will have a bromine number less than half that of the charging material with a resultant increase in lead susceptibility. In this manner the aviation characteristics of an olefinic gasoline may be improved.

It is, therefore, an object of our invention to produce a fraction boiling in the gasoline range having a bromine number of less than half that of the corresponding fraction of the charge.

It is a further object of our invention to produce from an olefinic naphtha a hydrocarbon product, that fraction of which boiling below the endpoint of the naphtha charge has a 1-C octane number with 4 ml. of tetraethyl lead per gallon at least 5 units higher than the corresponding leaded octane number of the charge. Furthermore for most satisfactory use in preparing aviation fuel blends, the 1-C octane number of the product with 4 ml. of tetraethyl lead per gallon should be in excess of 85 and preferably in excess of 90. The 1-C method is described in A. S. T. M. 614-41T.

It is another object of our invention to treat an olefinic gasoline fraction in the substantial absence of added higher boiling hydrocarbons to improve its aviation fuel characteristics. That is, the end boiling point of the charge is within the gasoline range.

The accompanying drawing is a graph showing the effect of temperature on 1-C octane number and bromine number, the curves of this graph being based on certain data from Tests 1 to 5 hereinafter described.

The catalysts which we have found suitable for this purpose comprise porous associations of silica with one or more compounds of elements whose oxides are refractory, such as alumina, zirconia, magnesia, thoria, ceria, etc. These cata-

2

lysts may be prepared synthetically from compounds of silicon and compounds which will give rise to the other refractory oxide, or they may be obtained from naturally occurring minerals. Thus, for example, the silica alumina composites which are employed in the present invention may be prepared by precipitation of hydrous silica and hydrous alumina from suitable solutions of compounds of silicon and aluminum, either by successive precipitation or by co-precipitation methods followed by drying and calcining. On the other hand, certain naturally occurring materials such as bentonite, montmorillonite, floridin, and other active clay like materials may be employed in the process of this invention preferably after activation by an acid treatment and/or calcination.

Although these catalysts have been previously used in some refining or treating processes, the purpose of these processes has been merely to remove relatively minor amounts of highly reactive and undesirable constituents of the charge, such as diolefins and sulfur compounds and has not been to effect any substantial reduction in the bromine number of the gasoline boiling range fractions to prepare a suitable aviation base blending stock. As previously noted, on the other hand, it is an object of this invention to produce from an olefinic gasoline a gasoline fraction having a bromine number less than half that of the corresponding fraction of the original charge and suitable as an aviation base blending stock.

The process of this invention is conducted at a temperature above 400° F. but below 650° F. and is preferably within the range of from 450 to 600° F. The pressures which are employed are such that at least a substantial portion of the material in the reaction is in the liquid phase and will therefore usually be above about 300 pounds per square inch. In general pressures below 1000 pounds are adequate, the higher pressures being employed at the higher temperatures in order to aid in maintaining a substantial liquid phase in the reaction zone. The space velocities which are employed are below about 15 and will ordinarily range from about 0.3 to 15 unit weights of charging oil treated per hour per unit weight of catalyst in the reaction zone. The preferred range is from about 0.5 to 5 units.

In the preferred operating range of this invention, the amount of cracking as measured by the accompanying gas formation is negligible and therefore almost 100% of the charge on a weight basis is recovered as a liquid. Since the amount of gas formation is negligible, the amount of catalyst deposit which is formed is also small when operating in the preferred range of temperature, pressure and space velocity. On the other hand, if temperatures are increased above 650° F., cracking begins to take place, gas and catalyst

deposit are formed in increasing amounts and in general, the operation is unsuitable for our purposes.

In one specific embodiment, the present invention relates to a method for reducing the olefin content of an olefin containing fraction boiling in the gasoline range which comprises contacting said fraction in the substantial absence of added higher boiling hydrocarbons with a catalyst comprising an association of silica and at least one compound of an element whose oxide is refractory, at a temperature of above 400° F. but below 650° F. without effecting substantial cracking, and at a pressure such that a substantial portion of the hydrocarbons in the reaction zone is in the liquid phase, to form a liquid product, that portion of which having an end boiling point corresponding to that of the fraction charged has a bromine number of less than half that of said fraction.

The charging stock which may be employed in this process may comprise any olefinic naphtha fraction, gasoline or pure olefinic hydrocarbon boiling in the gasoline range. Ordinarily, olefinic naphtha fractions or gasolines produced by cracking or reforming operations, preferably catalytic, will be employed since these charging materials are abundant and usually possess high initial octane numbers. As previously noted, the reaction is conducted in the substantial absence of added higher boiling hydrocarbons since these materials, as will be later demonstrated by specific examples, have been found detrimental.

The catalyst may be employed either in the form of granules, pellets or other preformed shapes, or in the form of a finely divided powder. In case granules are employed, the reactants may be continuously passed through a bed of the granular catalyst maintained at reaction conditions. If powdered catalyst is employed, the catalyst may be suspended in the reactant stream and conducted through a tubular reaction zone or through a vertical enlarged reaction zone in which the catalyst is maintained in turbulent motion by means of the upwardly rising reactants and conversion products.

The products from the reaction zone may be fractionated to separate a distillate of the desired end point from the bottoms. Any portion of the reaction products may, if desired, be returned to the reaction zone for further treatment.

Unlike other operations for producing aviation base stocks from olefinic hydrocarbons, the catalyst in this operation may be processed for a considerable length of time without having to regenerate. For example, times of processing may range up to about 75 hours more or less and a product having the necessary low bromine number will be obtainable. Usually however, times of processing longer than two hours are employed for the reason that the catalyst is still active at that time.

When regeneration is required, it may be accomplished in situ by passing oxygen containing gases through the catalyst bed, or the catalyst may be removed to an external zone, regenerated by contact with oxygen containing gases, and returned to the processing zone for further use.

The following examples illustrate the yields and quality of the aviation fuel stock which may be obtained when operating according to the process of the present invention.

Example 1.—In Tests 1 through 5, a 300° F. endpoint gasoline obtained by catalytic cracking

of gas oil was the charging material. In these tests, the charging material was passed over a silica alumina zirconia catalyst obtained by precipitation methods and the product from each test was fractionated to recover a 300° F. endpoint gasoline on which octane numbers and bromine numbers were obtained. These results of these tests are indicated below:

	Charg-ing stock	Test No.				
		1	2	3	4	5
15	Temperature °F.	300	475	520	581	639
	Pressure lbs./sq. in.	800	800	800	800	800
	Weight hourly space velocity	1.8	1.8	1.9	1.8	1.8
	Time of processing hours	18	18	18	18	18
	Distribution of product:					
	Per cent by weight of 300° F. E. P. gasoline	100.0	75.8	65.5	65.8	71.3
20	Per cent by weight residue	24.2	34.5	34.2	28.7	20.5
	300° F. E. P. gasoline:	95	57	26	20	27
	Br. No.	85.1	90.8	94.5	95.1	94.4
	Octane No., 1-C+4 ml. TEL/gal.	85.1	90.8	94.5	95.1	94.4
		92.0				

In each of the tests indicated above, the amount of gas that was produced was negligible and the amount of catalyst deposit was small, generally less than a few tenths of a percent by weight of the charging material.

It will be noted that the temperature in Test 1 was slightly below the preferred temperature range of this process and that the bromine number of the 300° F. endpoint product was greater than half the bromine number of the 300° F. endpoint charge. Tests 2 through 5, on the other hand, all resulted in the formation of 300° F. endpoint gasolines having bromine numbers less than half that of the charge, and it will be noted that the leaded 1-C octane number was improved in direct proportion to the bromine number reduction. It will also be noted that a minimum in the bromine number of the product was obtained at about 520° F. as in Test 3 and thereafter increased with increasing temperature. If temperatures of 650° F. or higher are employed, the rate of cracking is sufficiently great so that carbon formation is excessive and as a result the bromine number is not reduced the required amount for the long process periods. The data from Tests 1-5 are shown on the accompanying drawing.

Example 2.—In Test 6 a 275° F. endpoint gasoline obtained from catalytic cracking was the charging material. In this test, the gasoline charge was contacted with a catalyst comprising a calcined mixture of precipitated hydrous silica and precipitated hydrous alumina at the conditions indicated below and the following data

60 were obtained:

	Charging stock	Test 6
65	Temperature °F.	518
	Pressure lbs./sq. in.	600
	Weight hourly space velocity hours	2.2
	Time of processing hours	18
	Distribution of product:	
	Per cent by weight of 275° F. E. P. gasoline	100
	Per cent by weight of residue	83.6
70	275° F. E. P. gasoline:	16.4
	Br. No.	59
	Octane number, 1-C+4 ml. TEL/gal.	23
		99.7

In this test the amount of gas formation was negligible and the catalyst deposit amounted to about 1% by weight of the charge, indicating

that substantially no cracking had taken place. The high leaded octane number of the product indicated its extreme suitability as an aviation fuel blending stock.

Example 3.—In Test 7, shown below, the catalyst was a silica-magnesia composite prepared by impregnating alkali free silica hydrogel with magnesium nitrate and calcining to produce an active mass. The charging stock was a 278° F. endpoint gasoline obtained from catalytic cracking of a Mid-Continent gas oil. This catalyst, although not quite as active as the catalysts of the silica alumina and silica alumina zirconia type previously illustrated, nevertheless had an appreciable catalytic activity for this reaction. The results of the test are tabulated below:

	Charging stock	Test 7	
Temperature.....°F.		531	
Pressure.....lbs./sq. in.		800	
Weight hourly space velocity.....		1.8	
Time of processing.....hours		15	
Distribution of product:			
280° F. E. P. gasoline	per cent by weight	100	85.4
Residue.....do			14.6
280° F. E. P. gasoline:			
Br. No.		69	28
Octane number, 1-C+4 ml.	TEL/gal.	88.9	93.9

The amount of gas formation in Test 7 was negligible and the carbon yield amounted to about .25% by weight of the charge.

Example 4.—The following runs were made to determine the effect of adding a gas oil to the olefinic gasoline charge. In Test 8, an olefinic gasoline obtained by catalytic cracking of a Mid-Continent gas oil was treated at optimum conditions with a precipitated calcined silica-alumina-zirconia catalyst and the yields and quality of the products were determined. In Test 9, 60% of the same gasoline on a volume basis (55% on a weight basis) was blended with another portion of the same Mid-Continent gas oil that was the cracking stock for the gasoline, and was treated with another portion of the same catalyst used in Test 8 at comparable conditions. The results of the tests are shown below:

	Olefinic gasoline, charging stock	Test 8 without added gas oil	Test 9 with added gas oil
Temperature.....°F.		534	532
Pressure.....lbs./sq. in.		800	800
Weight hourly space velocity.....		1.7	1.9
Time of processing.....hours		15	20
Distribution of product:			
280° F. E. P. gasoline	per cent by weight	100	73.0
Residue.....do			27.0
280° F. E. P. gasoline:			
Br. No.		69	9
Octane Number, 1-C+4 ml.	TEL/gal.	88.9	91.4

As in the previous runs, substantially no gas was produced and formation of catalyst deposit was slight. It will be noted that the presence of the added gas oil in Test 9 was harmful in that the gasoline product had a higher bromine number and a lower leaded octane number than the

gasoline product which was obtained in test 8 in the absence of the added gas oil.

Example 5.—Tests 10 and 11 were made to determine the effectiveness of two different grades of Super Filtral (an acid treated bentonite) in effecting the production of an aviation base stock by the process of this invention. In each test, an olefinic gasoline obtained by catalytic cracking of a gas oil was contacted with the catalyst and the products of the reaction were analyzed to determine their characteristics. The results of these tests are shown below:

		Charging stock	Test 10	Test 11
15	Temperature.....°F.		534	534
Pressure.....lbs./sq. in.		800	800	
Weight hourly space velocity.....		2.1	2.1	
Time of processing.....hours		15	15	
20	Distribution of product:			
280° F. E. P. gasoline	Weight per cent	100.0	73.1	72.5
Residue.....do			26.9	27.5
280° F. E. P. gasoline:				
Bromine number.....		69	11	12
O. N., 1-C+4 ml. TEL/gal.		88.9	98.9	98.9

It is evident that the non-precipitated catalysts of the silica alumina type are very effective in accomplishing this reaction. It should be noted that in the above tests the amount of cracking was negligible and the catalyst deposit amounted to about 0.2% by weight of the charge.

We claim as our invention:

1. A process for reducing the olefin content of an olefinic distillate boiling in the gasoline range which comprises subjecting said distillate to the action of a catalyst comprising precipitated silica and precipitated alumina at a temperature above 400° F. but below 650° F. under a pressure sufficient to maintain a substantial portion of said distillate in liquid phase and at a weight hourly space velocity of from 0.3 to 15, whereby to form a gasoline fraction having a bromine number less than one-half that of said olefinic distillate, and recovering said gasoline fraction from the products of the treatment.

2. A process for reducing the olefin content of an olefinic distillate boiling in the gasoline range which comprises subjecting said distillate to the action of a catalyst comprising silica and zirconia at a temperature above 400° F. but below 650° F. under a pressure sufficient to maintain a substantial portion of said distillate in liquid phase and at a weight hourly space velocity of from 0.3 to 15, whereby to form a gasoline fraction having a bromine number less than one-half that of said olefinic distillate, and recovering said gasoline fraction from the products of the treatment.

3. The process as defined in claim 2 further characterized in that said catalyst contains alumina in addition to the silica and zirconia.

4. The process as defined in claim 1 further characterized in that said catalyst contains precipitated zirconia in addition to the precipitated silica and alumina.
